UNITED STATES PATENT OFFICE.

FRANZ XAVER MULLER-FICHTER, OF THANN, ALSACE, GERMANY.

DEVICE FOR CLEANING THE WATER-TIGHT BLANKETS OF CLOTH-PRINTING MACHINES.

965,117.

Specification of Letters Patent. Patented July 19, 1910.

Application filed September 21, 1909. Serial No. 518,835.

To all whom it may concern:

Be it known that I, FRANZ XAVER MULLER-FICHTER, a subject of the German Emperor, and resident of Thann i., Alsace, Germany, have invented certain new and useful Improvements in Devices for Cleaning the Water-Tight Blankets of Cloth-Printing Machines, of which the following is a full, clear, and exact description.

10 The present invention relates to a device for cleaning the counter-pressing rollers, of cloth-printing-machines and consists in the substitution for the ordinary watertight covering of such rollers of an endless watertight blanket guided on rollers. Instead of 15 the wiping and drying aprons ordinarily used for cleaning the counter-pressing roller, said blanket is itself, after each impression, passed through a system of washing and 20 cleaning rollers and thereupon subjected to a drying process before it again comes into contact with the counter-pressing roller.

The advantage of the invention is that 25 the endless washing blanket being made of watertight, tough material is far more easy to guide on its rollers than are the soft wiping and drying aprons which easily get displaced and therefore require frequent adjustment. Besides a more thorough cleaning 30 of the blanket will be effected by the arrangement employed in the present invention, than is the case when using wiping and drying aprons.

In the accompanying drawing a sample 35 form of construction of the improved arrangement is shown in a diagrammatic view.

The counter-pressing roller *l* of the printing-machine receives a covering *a*¹ which 40 consists of an endless watertight blanket running on guide-rollers *b* from and to the counter-pressing roller. This blanket is first washed by means of a roller *g* over which a spray pipe *g*¹ is arranged. It is then wiped by a rubber or felt roller *i* which rotates in a direction opposite to that of the blanket and which is, in its turn, cleaned by a brush-roller *f* and a squeezing-roller *h*. Having passed the roller *i* the blanket is 45 next subjected to the action of a scraper *k* which completes the cleaning of the same. It is thereupon conducted under a felt covered roller *p*, by which it is preliminarily

dried, the complete drying being effected by means of a series of perforated pipes *m* producing a hot air current through which the 55 blanket passes. In order to reduce the temperature imparted by the hot air current to the blanket, the latter is subsequently conducted over a series of pipes *n* which produce a cold air current. I thus dispense 60 with a rotating wiping band device and accomplish a more reliable and perfect cleaning of the blanket and more satisfactory result in the printing.

The process of cleaning the dirty blanket 65 during the printing is the following: The endless blanket *a*¹ passes during the printing around the counter-pressing roller *l*, and between the latter and the fabric to be printed. Having passed the printing rollers, the 70 blanket is conducted to the cleaning device where the color adhering to it is first damped by the rollers *g* and then removed by the roller *i*. The brush roller *f*, working in opposite direction to the roller *i*, washes the 75 color off the latter, and the water adhering to same is pressed out by the roller *h*. The final cleaning of the blanket is effected by the scraper *k*. After the blanket *a* has in this way been cleaned, the drying-process 80 commences, which consists in causing the felt covered drying-cylinder *p*, to rub off the blanket *a*¹, whereupon the latter for the purpose of being thoroughly dried passes over guide-rollers *b* along the system of 85 tubes *m* provided with nozzles through which a hot air current emanates. The system tubes *n*, along which the blanket is subsequently conducted, effects the cooling of the same. After the blanket has been thus 90 cleaned and dried it again passes around the counter-pressing roller *l*.

I claim:

A device for cleaning the water-tight 95 blankets of cloth printing machines, comprising in combination with an endless blanket running on guide-rollers, a roller adapted to wash the blanket, a spray pipe supplying water to said roller, a wiping roller arranged next to said washing roller, 100 a scraper arranged next to the wiping roller to complete the cleaning, a brush roller adapted to wash the wiping roller a press roller for pressing the water out of the same,

a felt-covered roller for preliminarily drying the blanket, a series of pipes adapted to produce a hot air current for completely drying the blanket, and a series of pipes adapted to produce a cold air current for cooling the same, substantially as set forth.

5 In testimony, that I claim the foregoing

as my invention, I have signed my name in the presence of two subscribing witnesses.

FRANZ XAVER MULLER-FICHTER.
